UNITED STATES PATENT OFFICE.

FRED. W. KEIFEL, JR., OF LOUISVILLE, KENTUCKY.

DESIGN FOR A FIRE-PLACE.

SPECIFICATION forming part of Design No. 20,033, dated July 15, 1890.

Application filed June 16, 1890. Serial No. 355,690. Term of patent 7 years.

To all whom it may concern:

Be it known that I, FRED. W. KEIFEL, Jr., a citizen of the United States, residing at Louisville, in the county of Jefferson, State of Kentucky, have invented certain new and useful Improvements in Designs for Fire-Places, of which the following is a specification, reference being had therein to the accompanying drawings.

10 Figure 1 is a front view of my fire-place with the summer front removed. Fig. 2 is a like view with the summer front in position.

A is the crown ornamented by ivy-leaves a and berries b, and B is the frame ornamented 15 by suitable leaves and berries similar to those of the crown and at the upper corners by birds c on boughs b.

C is the ash-screen ornamented, as shown, and having a lifter e.

D is the basket.

20 E is the summer front having surrounding ornamentations and upon its center by a bird c on a bough d.

F is the fender.

The appearance of the design in general is 25 illustrated in the photographs, and is rich and beautiful.

What I claim is—

The design for a fire place or grate, substantially as shown.

30 In testimony whereof I affix my signature in presence of two witnesses.

FRED. W. KEIFEL, JR.

Witnesses:
